UNITED STATES PATENT OFFICE.

CHARLES KANARIAN, OF NEW YORK, N. Y.

PHOTOPRINTING MACHINE.

Application filed April 8, 1925. Serial No. 21,589.

The object of my improvement is to provide a simplified construction, operatively manipulated either by power driven mechanism or by hand, as preferred, so as to facilitate as much as possible the work to be performed, as well as to combine and limit in one construction the elements of light and time exposure, so essential to the photo-printing art, thereby securing greater uniformity of results and a better grade of article produced for the market in increased quantities under similar conditions of time and labor.

The novel and useful features of the improvement will more readily appear from the forthcoming detailed description to be read in conjunction with the drawings and the claims.

Figure 1 is a perspective front and side view of the machine; Fig. 2 is a side view; Fig. 3 is a front view; Fig. 4 is a perspective of the printing frame with parts removed; Fig. 5 is a perspective of the cam-operating paper dropper; Fig. 6 is a detail of Figure 4; Fig. 7 is a cross-section of Fig. 2; Fig. 8 is a perspective of the printing frames C and c; Fig. 9 shows the ratchet and pawl; and Fig. 10, a plan view of multiple machines in a single frame.

The upright frame A and the auxiliary frame A' support the motor driving elements E and the driven elements F by means of brackets 1, 2, and 3, Figure 1, which may be constructed out of any substantial material in the manner shown for convenience of individual needs or as necessity may require.

The light box B is fitted into the frame A, Figures 1 and 7, and is completely enclosed, having an adjustable body b, adapted to carry the electric bulbs 15 and to be moved forward or rearward relative to frame C by means of crank 16 rigidly secured to the threaded rod 17, which engages threads in plate 18 attached to body b, so as to regulate the intensity of the light desired to penetrate the translucent glass 19, clamped firmly in the frame C with the photographic plate that is to be reproduced by the co-action of the sensitized paper or print compressed by platen D in contact therewith and artificial light emanating from the light box B.

The open rectangular frame C, Figs. 4 and 8, is grooved along the inner margin to receive the translucent glass 19, and the photographic plate or film, as the case may be, which are clamped together by the three-sided frame c, adjustable therewith, by means

of the thumb screws 13 and the coil springs 14, the bottom section of c being absent so as to admit of the vibratory action thereunder of the paper dropper 11, Fig. 5, and aid in the rapid removal of the sensitized paper or print, after exposure, into the receptacle beneath, when the paper dropper 11, secured to the guide-rods 10, 10 and held in contact with the cams 7, 7, Fig. 5, is oppositely disposed or extended by spiral expansion springs 10a. The sectional three-sided frame c Fig. 8 is a most important feature of the clamping mechanism mentioned, as so constructed, for the reason that there is no bottom section to obstruct, or interfere with, the paper or print on being released, as stated, in dropping instantaneously and automatically into the receptacle below.

The hinged-platen D is adapted to fit inside of the frame c to admit of the necessary compression on the paper print in contact with the photographic plate or film, is secured in position on stanchion G by the leaf springs 12, Figs. 2, and 7, so to operate, and is faced or surfaced by any soft flexible substance, such as felt or crude sheet rubber, designated d, to give the requisite resiliency against too firm or over-compression on the photographic plate and the translucent glass 19 and consequent shattering of the glass and the destruction of the photographic plate or film.

Stanchion G, Figs. 1, 2 and 3, is so constructed as to carry platen D on the upper or outer end to which it is secured by the leaf-springs 12, Fig. 2, and by the lower or inner end to control the electric contact switch 20 and is so fulcrumed as to operate reciprocally by cam 8 through each cycle platen D over against the paper-print, photographic plate or film and the glass 19, all clamped together in the frame C, which is interposed therebetween and the light box B, Fig. 7, and the oppositely disposed contact switch 20 to light simultaneously therewith the electric bulbs 10 in the light box B in order to throw artificial light on the photographic plate or film at the instant of contact of platen D with the sensitized paper or print, that is compressed thereby, as stated, against the photographic plate or film in the frame C.

The glass 19 is rendered translucent for the purpose of diffusing light emitted from the bulbs 15, and is fitted into the grooved inner margin of the supporting frame C, Figs. 4 and 8, together with the film or photographic plate and all are clamped thereto by means

of the thumb-screws 13 in frame *c* under tension of spiral springs 14 to prevent crushing or over-pressure. Frame *C* is then positioned at the head of the light box *B*.

5 The power element may be of a general character of a single motor, as *E*, Fig. 1, of the ordinary type of dynamo construction, having sufficient power to drive the worm 5, Figs. 1, 2 and 3, engaging worm-gear 6 on the 10 cam shaft *F*. Rigidly secured to the shaft *F* are the two cams 7, co-acting through each cycle with the cam-driven members 9 on the guide rods 10 to vibrate the paper dropper 11 to release the paper print. Cam 8 is also rigidly secured to the shaft *F* and is revoluble therewith, but disposed in a different arc with cams 7 so as to reciprocate in rotation and sequence the fulcrumed stanchion *G*, the hinged platen *D* and the electric contact 20, 20 which limits the time-exposure of light from bulbs 15 on the sensitized paper, the intensity of the light being regulated by the forward and rearward adjustment of body *b* by crank 16 in the light box *B*. The leaf-springs 12, 25 interposed between stanchion *G* and platen *D* further serve to relieve too firm compression or overpressure from platen *D* with its soft flexible surface or facing, designated *d*, on the sensitized paper in contact with the film, 30 photographic plate or glass 19, in frame *C*.

The combinational elements of my improved photo-printing machine as assembled and in operation may now be briefly set forth. Each cycle or rotation presents successive 35 steps or stages of operation quite analogous to the paper printing art generally.

The photographic plate or film is clamped by the supplemental frame *c* in frame *C*, Fig. 8 as described, which is firmly secured in the 40 head of the light box *B*. The motor driving element, as motor *E*, regulates the speed during each arc of the rotation of the cam-shaft *F* according to the work to be performed or being performed, the length of time exposure of the artificial light from bulbs 15, and the pause or dwell of the reciprocating stanchion *G* in open position to enable the operator to place the sensitized paper to be 45 printed properly in position over the film or plate and against the paper dropper 11, Fig. 5, and the supplemental frame *c*, which serve as a register or guide in properly manipulating the paper-print to insure accuracy in position and uniformity of the printed product.

The two cams 7, Fig. 5, through each revolution of the cam-shaft *F* acting on the cam-driven members 9 move to and fro the paper dropper 11 rigidly secured to guide rods 10 under the frame *C*, the glass 19 and the plate or film, thus holding the paper print in position, in advance of the axial rotation of the fulcrumed stanchion *G* by a like or similar action of cam 8, to which is attached at the 60 upper end by the leaf-springs 12 the hinged

platen *D*, adapted to contact by such co-action the sensitized print over the plate or film at the same instant that the electric contact switch 20 on the opposite end connects the current of electricity to light the bulbs 15 in the light box *B*, whence emanates the artificial light through glass 19 to reproduce the photograph or imprint the film on the sensitized paper or print in the usual manner adopted in the photographic art. On the 70 completion of the revolution or cycle of the cam-shaft *F* the paper dropper 11 is released by the cams 7 and extended by the springs 10^a, presenting an opening or space under the frame *c* and the platen *D*, through which the paper falls. Consecutively stanchion *G* is released, disconnecting the contact switch 20 and carrying with it the hinged-platen *D* to return to open position. Another sheet of print or sensitized paper is inserted and the 80 mechanical steps or stages of the cycle or revolution are renewed. If desired, a ratchet and pawl may be operably connected to the worm-gear 6 and the cam-shaft *F*, as in Fig. 9, or any other suitable device, to enable the 85 operator to stop or disconnect the power driving element at any desired position or to prevent accidents, as the case may be.

Having described the novel and useful features of my improvement in photo-printing 90 machines, I claim:

1. In a photo-printing machine, a main frame for support, an auxiliary frame secured thereto, a power driving element on the auxiliary frame, a power driven cam-shaft 100 engaged therewith and bracketed to the main frame, cams rigidly secured to the cam-shaft, a paper dropper integral with guide-rods deflected to form cam-driven members to be reciprocated thereby, a hinged platen, a printing frame, a contact switch, a stanchion fulcrumed so as to operate at the upper end, said hinged-platen against sensitized prints suitably disposed over a photographic plate or film clamped in a printing frame, and vibrated by a cam on the cam-shaft to connect instantaneously a contact switch for artificial light oppositely disposed on the lower end thereof, a light box, said open rectangular printing frame and a supplemental frame 110 serving to clamp plates or films therebetween placed at the head of a light box, said light-box having a movable section therein, adjustable forward and rearward relative to the plate or film, said movable section being constructed with sockets to engage electric light bulbs in contact with said electric switch and electric light bulbs in the adjustable section of the light box operably combined with the contact switch so as to supply artificial 115 light by the co-action of the reciprocating stanchion.

2. In a photo-printing machine, a main frame for support, an auxiliary frame carrying power-driving elements, power driving 120

- elements thereon, driven elements bracketed to the main frame, a plurality of cams secured to the driven elements, a plurality of paper droppers rigidly secured to guide-rods 5 flected to form cam-driven members, a plurality of hinged platens, a plurality of cam-driven stanchions fulcrumed so as to operate said hinged-platens serially arranged against sensitized prints suitably placed over photographic plates or films simultaneously with electric switches oppositely disposed thereto, a plurality of open printing frames adapted to clamp photographic plates or films therebetween and placed serially at the head of consecutively arranged light-boxes, a plurality of contact switches on said vibrating stanchions to operate electric bulbs, a plurality of light-boxes having movable sectional members therein, which are constructed with sockets to engage electric bulbs actuated through said electric contact switches, said sectional members being adapted to regulate the intensity of light by proximal and distal adjustment relative to the printing frame and means operably reciprocating said elements combinationally and consecutively for printing photographs.
3. In a power driven photo-printing machine comprising a main frame and an auxiliary frame, driving members attached to the auxiliary frame, driven members bracketed to the main supporting frame, a stanchion fulcrumed to the main supporting frame, cams rigidly secured to the driven members, a paper-dropper, a hinged platen and an electric contact switch oppositely disposed on the ends of said fulcrumed stanchion operated consecutively by said cams, an open rectangular frame adapted to hold a photographic plate or film therein, a light box for artificial light said open rectangular frame being firmly secured in the head of the light box, an adjustable section in the body of the light box constructed to carry a plurality of light bulbs, said contact switch operating said lights and means for adjusting said movable section proximally and distally to intensify and diminish the light.
4. In a power driven photo-printing machine comprising a main frame and an auxiliary frame, driving members attached to the auxiliary frame, driven members bracketed to the supporting frame engaged with said driving elements and controlled thereby, cams rigidly secured to said driven members, guide-rods integral with cam driven members, spiral springs therebetween and the supporting frame, a paper dropper integral with the guide-rods and reciprocated by the co-action of the cams and spiral springs, a hinged-platen having a resilient surface thereon to contact with said plate, a fulcrumed stanchion with said hinged-platen and an electric contact switch oppositely disposed on the ends thereof vibrated by said cams, the contact switch being adapted to contact simultaneously with the compression of the hinged-platen against sensitized paper on the plate or film secured in the frame at the head of the light box, said light box constructed to engage electric light bulbs, artificial light in the light box and means for controlling the artificial light on the sensitized print to reproduce the photograph.
- In witness whereof I have hereunto set my hand in the execution hereof.

CHAS. KANARIAN.
